UNITED STATES PATENT OFFICE.

JOACHIM MAIDHOF, OF NEW YORK, N. Y.

DESIGN FOR TRIMMING.

SPECIFICATION forming part of Design No. 18,369, dated June 5, 1888.

Application filed February 3, 1888. Serial No. 262,942. Term of patent 3½ years.

To all whom it may concern:

Be it known that I, JOACHIM MAIDHOF, of the city, county and State of New York, have invented and produced a new and Original 5 Design for Dress-Trimming, of which the following is a specification.

The leading feature of my design consists of cord-like lines curved to represent a palm-leaf, with scroll-like lines representing loops surrounding the outer edge, and cord-like lines in imitation of loops within the space surrounded by the palm-figure.

Reference is to be had to the accompanying drawing, forming a part of this specification, 15 in which the figures represent plan views of my design.

In the figures A and B, *a* represents curved cord-like lines in imitation of "palm-leaves," *a'* scroll lines around the outer edge of the palm-

like figures and representing a series of connected loops, and *a''* cord-like lines within the space surrounded by the palm-like figures and in imitation of a cluster of loops and star-like figures. The figures A and B are represented as graduated and arranged in series. 20 25

I claim—

The design for dress trimming herein shown and described, the same consisting of a curved cord-line representing a palm-leaf, scroll-like lines surrounding the palm-leaf figure 30 and representing a series of loops, and cord-like lines within the palm-leaf figure and representing a cluster of loops and a star-like figure.

JOACHIM MAIDHOF.
